DESIGN FOR A LAPEL PIN OR THE LIKE

Donald Campbell, Medford, Oreg.

Application October 15, 1948, Serial No. 149,122

Term of patent 14 years

(Cl. D29—11)

To all whom it may concern:

Be it known that I, Donald Campbell, a citizen of the United States of America, residing at Medford, in the county of Jackson and State of Oregon, have invented a new, original, and ornamental Design for Lapel Pins or the like, of which the following is a specification, reference being had to the accompanying drawing, forming a part thereof.

In the drawing:

Figure 1 is a front elevational view of a lapel pin or the like, showing my new design.
Figure 2 is a top plan view.

Figure 3 is a longitudinal section taken on the line 3—3 of Figure 1.

I claim:

The ornamental design for a lapel pin or the like, as shown.

DONALD CAMPBELL.
